Patented Feb. 23, 1971

219,956

PACKAGING TRAY FOR COOKIES OR THE LIKE

Philip M. Clemens, 1835 Pemberton Drive,
Fort Wayne, Ind. 46805

Filed Jan. 5, 1970, Ser. No. 20,758

Term of patent 14 years

Int. Cl. D9—04

U.S. Cl. D9—189

FIG. 1 is a perspective view of a packaging tray for cookies or the like embodying my new design;

FIG. 2 is a top view thereof; and

FIG. 3 is a side elevation thereof.

I claim:

The ornamental design for a packaging tray for cookies or the like, as shown.
